(57) **CLAIM**

The ornamental design for a plant pot drainage tray, as shown and described.

DESCRIPTION

FIG. 1 is a perspective view of a plant pot drainage tray. FIG. 2 is a front elevation view, the rear, left side, and right side views being identical thereto; FIG. 3 is a top plan view thereof; and, FIG. 4 is a bottom plan view thereof. The broken lines showing flowers show portions of the article forming no part of the claimed design.
